US0D1005953S

(12) **United States Design Patent** (10) **Patent No.:** **US D1,005,953 S**
(45) **Date of Patent:** **** Nov. 28, 2023**

(54) **MAGNETIC CORE**

(71) Applicant: **Delta Electronics (Shanghai) CO., LTD**, Shanghai (CN)

(72) Inventors: **Haibin Song**, Shanghai (CN); **Qi Fu**, Shanghai (CN); **Daofei Xu**, Shanghai (CN); **Jinfa Zhang**, Shanghai (CN)

(73) Assignee: **Delta Electronics (Shanghai) CO., LTD**, Shanghai (CN)

(**) Term: **15 Years**

(21) Appl. No.: **29/769,321**

(22) Filed: **Feb. 4, 2021**

Related U.S. Application Data

(62) Division of application No. 29/697,318, filed on Jul. 8, 2019, now Pat. No. Des. 912,626.

(30) **Foreign Application Priority Data**

Jan. 15, 2019 (CN) 201930021079.X

(51) **LOC (14) Cl.** **13-02**

(52) **U.S. Cl.**

USPC **D13/118**

(57) **CLAIM**

The ornamental design for a magnetic core, as shown and described.

DESCRIPTION

FIG. 1 is a front view of the new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines in the drawings depict portions of the magnetic core that form no part of the claimed design.

1 Claim, 7 Drawing Sheets
